UNITED STATES PATENT OFFICE

2,103,320

ABRASIVE HOLDER

Edward V. Corff, Chicago, Ill.

Application September 6, 1935, Serial No. 39,429

1 Claim. (Cl. 51—187)

My invention relates to abrasive devices and more particularly it relates to a device adapted for manual manipulation to sharpen cutlery and for use in abrasive contact with numerous other articles.

The invention has as one of its objects the provision of an improved abrasive device of the kind described providing novel means for removal and renewal of the portion of the device providing the abrasive surfaces.

Another object of the invention is the provision of an improved abrasive device of the kind described which is inexpensive to manufacture, efficient, durable and satisfactory for its intended purpose.

Many other objects and advantages of the construction herein shown and described will be obvious to those skilled in the art from the description herein given.

To this end my invention consists in the novel construction, arrangement and combination of parts herein shown and described and more particularly pointed out in the claim.

In the drawings, wherein like reference characters indicate like or corresponding parts:

Fig. 1 is a plan view of one form of an abrasive device embodying the principles of the invention;

Fig. 2 is a view along the line 2—2 of Fig. 1;

Fig. 3 is a view along the line 3—3 of Fig. 1;

Fig. 4 is a view along the line 4—4 of Fig. 1;

Figs. 5, 6, 7, and 8 are, respectively, cross-sectional views of modified forms of the device shown in Fig. 1;

Fig. 9 is a plan view of another alternative form of a device embodying the principles of the invention;

Fig. 10 is a view along the line 10—10 of Fig. 9; and

Figs. 11 and 12 are, respectively, cross-sectional views of modified forms of the device shown in Fig. 9.

Referring now more particularly to the drawings, the numeral 10 generally designates an elongated hollow member preferably formed of a thin sheet of metal with one end arranged to form a handle piece 11 of elliptical or other suitable cross-section, the other end forming a member 12 on which an abrasive sheet 13 is adapted to be removably secured. The member 12 is preferably formed as shown in Fig. 4 wherein one edge is substantially semicylindrical and of the same curvature and in alignment with the corresponding edge of the handle piece 11. The opposite side walls of the member 12 are substantially

straight with their marginal edges closely spaced to form a narrow slit 14.

The abrasive sheet 13 has a length preferably slightly less than the length of the member 12 and a width in excess of the overall width of the metal sheet forming the member 12, the excess in width being such that the opposite marginal edges 15 of the abrasive sheet project into the hollow member in a substantial amount as shown. The abrasive sheet 13 is preferably mounted on 10 the member 12 by first folding it to substantially the shape shown in Fig. 4 and then placing the folded sheet over the open end of the member with the marginal edges 15 projecting through the slit 14. The width of the slit 14 is slightly less than that of a double thickness of the abrasive sheet 13 so that the edges 15 are spring pressed together in the slit 14 by the resiliency of the side walls of the member 12.

The slit 14 is slightly inclined and convergent 20 towards the open end of the member 12, and, as a result, the sheet 13 is stretched laterally as it is drawn over the member 12 and insures a close, tight fit therewith. The described construction adapts the device for quick and easy removal for 25 renewal of the abrasive sheets 13 as required.

In the modified forms of the device shown in plan in Fig. 1, the member 12 is shown in Fig. 5 as elliptical in cross-section; in Fig. 6 as substantially rectangular; in Fig. 7 as triangular, 30 and in Fig. 8 as circular. In each case, the contiguous edges of the sheet forming the member 12 are closely spaced to provide a slit 14 having a width less than a double thickness of the abrasive sheet 13 whereby the resiliency of the member 12 spring presses the marginal edges 15 in close fitting contact sufficiently to hold the sheet 13 in position and to permit its easy removal.

An alternative embodiment of the invention is shown in plan in Fig. 9 and in cross-section in 40 Fig. 10, as comprising a body member 15 of solid material and a handle member 16 fastened to the body member in any suitable manner. The body member 15 may be constructed of wood or any suitable composition such as Bakelite and is 45 shown in Fig. 10 as substantially circular in cross-section and as providing a longitudinal recess 19. A pair of curved plates 18 are mounted in recesses provided for that purpose, one on each side of the recess 19, with the outer peripheries of the plates forming a continuation of the curved surface of the body member. The plates 18 are slightly resilient and their spacing is slightly less than a double thickness of an abrasive sheet 17. The side of the member 18 on 50 55

which the plates 19 are mounted converges perceptibly towards the center from the handle member towards the opposite end. The abrasive sheet 17 is mounted on the body member by tucking its longitudinal edges into the recess 19 at the outer end of the device with the sheet closely encircling the body member and then moving the sheet towards the handle member. The plates 18 yield to permit the entrance of the double thickness of the sheet 17 and the sheet is thereby caused to closely fit the body member and is held in position by the spring pressure of the plates.

In Fig. 11 the body member is shown as rectangular in cross-section and provided with a longitudinal recess 21 flanked on each side by a slightly resilient plate 22 fastened to the body member in any suitable manner. The adjacent edges of the plates 22 are spaced to receive and compress a double thickness of the sheet 17 which is mounted on the body member in the same manner as described for the form shown in Fig. 10. The sides of the body member adjacent the recess 22 are also slightly convergent toward the body member from the handle outwardly.

In Fig. 12 the body member 15 is wedge-shaped in cross-section with one angular edge cut away. The sides of the body member adjacent the cut-away portion are bounded by plates 25 fastened thereto in any suitable manner with their edges converging and providing a space slightly less than a double thickness of the abrasive sheet 17.

The sides of the body member 15 are also slightly tapered towards the outer end and the sheet 17 is mounted on the body member with the longitudinal edges tucked into the space 24

bounded by the plates 25 and the body member. Upon moving the sheet 17 to cover the body member, it is stretched taut and held in operative position by spring pressure exerted by the plates 25.

Thus it will be seen that I have provided an improved abrasive device forming a mounting for removably securing abrasive sheets and novel means for securing the sheets in position and permitting their easy removal for renewal.

Having thus described my invention, it is obvious that various immaterial modifications may be made in the same without departing from the spirit of my invention; hence I do not wish to be understood as limiting myself to the exact form, 15 construction, arrangement and combination of parts herein shown and described or uses mentioned.

What I claim as new and desire to secure by Letters Patent is:

An article of the kind described comprising an elongated hollow body member having one end forming a handle and the other end providing a slightly tapered surface uniformly convergent away from the handle, said tapered end having a narrow longitudinal recess or open seam terminating in its smaller end, the side walls of the recessed portion being resilient and so spaced that opposite edge portions of an abrasive sheet may be inserted in the open end of the recess and the sheet drawn longitudinally over said tapered portion to a position wherein it is disposed about and closely fits said tapered surface with its inserted edge portions held in spring pressed engagement by the bounding edges of said recess.

EDWARD V. CORFF.
